DESIGN FOR A TRAFFIC SIGNAL

Gordon Muir, Grosse Pointe Park, Mich.

Application November 23, 1938, Serial No. 81,309

Term of patent 14 years

To all whom it may concern:

Be it known that I, Gordon Muir, a citizen of the United States, residing at Grosse Pointe Park, county of Wayne, in the State of Michigan, have invented a new, original, and ornamental Design for a Traffic Signal, of which the following is a specification, reference being made to the accompanying drawing, forming part thereof.

Fig. 1 is a perspective view of a traffic signal showing my new design,

Fig. 2 is an enlarged front elevational view; and Fig. 3 is a top plan view thereof.

In the drawing the sides opposite to those shown in Fig. 1 are similar.

The characteristic feature of the design resides in the traffic signal shown having a facing comprised of a plurality of signal elements arranged as shown, said elements being lined for color as indicated on the drawing.

I claim:

The ornamental design for a traffic signal, as shown and described.

GORDON MUIR.
